F. WERMES

CONNECTING ROD BEARING WRENCH

Filed June 25, 1923

Inventor
Frank Wermes
by Clarence E. Melville
Atty

UNITED STATES PATENT OFFICE.

FRANK WERMES, OF AURORA, ILLINOIS.

CONNECTING-ROD-BEARING WRENCH.

Application filed June 25, 1923. Serial No. 647,450.

This invention relates to improvements in connecting rod bearing wrenches, and consists of the matters hereinafter described and more particularly pointed out in the appended claim.

The primary object of the invention is to provide a simple and efficient wrench by means of which the fourth connecting rod bearing of a Ford automobile engine, may be quickly tightened up by working upon the same through the inspection opening in the crank case bottom.

A further object of the invention is to so pivotally connect the socket head and the handle bar of the wrench, that the socket head is capable of a limited swinging movement on the handle bar from a position substantially at a right angle thereto, to a position less than an angle of 90° therefrom, so that the socket may be more easily applied to the otherwise almost inaccessible nuts on the bearing, from outside the inspection opening of the crank case.

These objects of the invention as well as the advantages of the improved wrench will more fully appear as I proceed with my specification.

In the drawings:—

Fig. 1 is a view of a Ford engine, partly in elevation and partly in section and illustrates the application of my improved wrench to the nuts of the fourth connecting rod bearing thereof.

Fig. 2 is a view partly in elevation and partly in section, on an enlarged scale, of my improved connecting rod bearing wrench.

Fig. 3 is a view of the parts shown at the left hand end of Fig. 2 with said parts shown in changed relation.

Fig. 4 is a top plan view of the improved wrench.

Fig. 5 is a detail sectional view on an enlarged scale as taken on the line 5—5 of Fig. 2.

The engine of a Ford automobile, by reason of its compact design, often presents difficulties to the garage man and mechanics in making repairs thereon, which are almost insurmountable unless the engine is dismantled or taken down. One of the most difficult jobs in making repairs and adjustments on such an engine without dismantling the same, is the tightening up of the connecting rod bearings and especially the connecting rod bearing of #4 cylinder, which is quite inaccessible through the inspection opening

in the bottom of the crank case. The ordinary "monkey" and S shaped wrenches are impractical for use through this opening because even if opposite sides of the nuts happen to be in an angular position on the bearing bolts wherein either of said wrenches can be applied, there is not enough room in the crank case to permit a sufficient swing of the wrench so that it may be again applied, when it is desired to take a new hold or grip upon said nuts. Many ingenious devices have been designed to meet the conditions of inaccessibility but they have failed for one reason or other.

The wrench of the present invention is especially adapted for use in tightening up #4 connecting rod bearing of a Ford automobile engine by working upon the same through the inspection opening in the crank case, the parts of the wrench being so constructed with reference to the engine as to permit operation of the same from within the crank case when working on said particular bearing. It will be understood, of course, that the wrench may also be used in tightening up the nuts on the other connecting rod bearings with equal, if not a greater facility.

The improved wrench comprises a handle 85 bar 5 and a socket head 6 connected thereto in a manner as will later appear. The handle bar 5 is made from a relatively long, steel rod which is flattened at one end on opposite sides to provide a part 7 which exceeds 90 in one direction the diameter of the rod, but is less than said diameter in a direction at a right angle to the first direction. In said flattened end part 7 is provided a transverse aperture 8 arranged in the plane of the axis 95 of the handle which is midway between, and top and bottom edges 9 and 10 of said flattened end. One corner of said flattened end part 7 is cut away at an angle to provide an inclined shoulder or edge 11 which merges 100 into the top edge 9 of said flattened end. The other end 12 of the handle is bent upwardly in the plane of the flattened end for a purpose to appear later.

The socket head 6 is made from a relatively short cylindrical piece of steel of a diameter greater than that of the handle 5. One end (the bottom) of said socket is bifurcated to provide a transversely extending groove 13 of a depth equal to the greater 110 diameter of the flattened end 7 of the handle bar and is of a width corresponding to the

lesser diameter of said flattened end so that said end may be inserted into said groove between the ears 14 on opposite sides thereof. In said ears are provided aligned apertures 15 which are adapted to register with the hole 8 in said flattened end 7 to receive a pin 16 which is upset at its ends in said ears. Said pin provides the axis about which the socket head 6 is capable of a limited rocking or swinging movement with respect to said handle, from a position substantially at right angles to the handle bar to a position less than 90° from the first position, the edges 9 and 11 together with the top transverse wall of the groove 13 providing stops to arrest the head in either position. In the opposite end of the socket head which is slightly tapered, is provided a hexagonal recess 17 and below the same is an annular recess 17^a of smaller diameter.

The operation of my improved wrench when used upon a #4 connecting rod bearing of a Ford engine is as follows:—18 indicates the engine of a Ford automobile which includes a crank shaft 19 and connecting rods 20, 21, 22 and 23 respectively, which connects the associated pistons and the crank arms of said crank shaft together. The bottom ends of the connecting rods are formed to provide half bearings and associated therewith are bearing blocks, said parts being secured together about the crank arms by bolts 24. On said bolts are nuts 25. When the bearing parts become worn and it is desired to "take up" or tighten said bearings, the cover for the inspection opening 26 in the bottom of the crank case is removed. The bearings of connecting rods 20, 21 and 22 may be easily gotten at, through said opening but the bearing of connecting rod 23, usually turned by garage men and mechanics as "#4 connecting rod bearing" is almost inaccessible by reason of its location back of the rear end of the inspection opening and by reason of the close proximity of other parts of the engine. In using my improved wrench on said bearing, I turn the crank shaft over, (by means of the starting crank) so that the associated piston is about one inch from its top-most position. This swings the bearing for the connecting rod 23, to one side of the median line of the engine and likewise swings the bearing for the connecting rod 22 to the opposite side of said median line, above the inspection opening 26 which is quite narrow. The wrench is then grasped by its handle bar and inserted through the inspection opening with the socket directed toward the bearing of connecting rod 23, the socket having been positioned on the handle in a plane at a right angle to the inclined surface or edge 11, which will engage with the top wall of the transverse groove 13 in said socket, as shown in Figs. 1 and 3. This permits the oper-

ator's hand to be outside the crank case so that he can position the socket 6 on the nut 25, the bent end 12 of the handle freely passing the radius rods 27 which are arranged just below the crank case at this point and connect the crank case and front axle of the automobile together.

Should it now be attempted to swing the handle bar 5 of the wrench to tighten up said nut, said swing would be limited by 75 striking the sides of the inspection opening so that the nut could not be turned the required 60° and it would be impossible to get a new bight on the nut.

After the socket has engaged the nut 25 80 on said connecting rod bearing, the handle bar is swung about the pin 16, upwardly through the inspection opening 26 into the crank case and into the position shown in dotted lines in Fig. 1 when said handle bar 85 will be arranged in the back of the bearing for connecting rod 22. With the parts in this position the bent up end 12 of the handle will be arranged in a plane between the bearings of the connecting rods 21 and 90 22 and below the center bearing for the crank shaft, where there will be room for the operator's hand. The wrench is then swung through an arc substantially 60° without engaging other adjacent parts of 95 the engine, after which the wrench is removed and again positioned on the nut so that it may again be turned another 60°. It is apparent that the limited relative movement between the handle and the socket 100 permits the use of the sense of "feeling" in positioning the socket head on the nut, and also permits positioning said head while the hand holding the wrench is outside of the crank case, after which it can be swung into a position wherein the swing of the wrench is not liable to make the socket slip off the nut. By making the socket relatively short in length, this tendency toward slipping off is further eliminated. When the socket is 105 on the nut, the bottom end of the bolt 24 projects into the smaller recess 17^a in the head so that the full depth of the hexagonal recess 17 engages the nut 25. By forming the end 12 of the handle as described, it will 110 freely pass the radius rods beneath the engine.

The improved wrench is simple in construction, (comprising only three parts) is efficient in operation, and especially meets the needs of garage men and mechanics for an efficient wrench, by means of which #4 bearing of a Ford engine may be quickly tightened by working through the inspection opening. It is so proportioned as to withstand without bending, such strain as it is possible to impose upon the same when used for the purpose intended.

While in describing my invention I have referred to the same, as by way of illustra-

tion, as especially adapted for use upon a particular bearing but it is also advantageous in working upon the other bearings of said engine.

5 I claim as my invention:—

A connecting rod bearing wrench, comprising a handle bar flattened at one end and having at that end a straight top edge, with one corner cut away to provide an angularly disposed edge which merges into said top edge, a short socket head having spaced ears with a groove between with a flattened base at the bottom of said groove, and a pivot pin

extending transversely through said flattened end of the handle bar and said spaced ears, the base of said groove in the socket head being adapted by the location of the pivotal axis of said pin with reference thereto for selective engagement with said angularly disposed edge and top edge of the flattened end of the handle bar selectively.

In testimony that I claim the foregoing as my invention, I affix my signature this 20th day of June, A. D. 1923.

FRANK WERMES.
